ATTORNEY

UNITED STATES PATENT OFFICE.

FURMAN M. KANDLE, OF ATLANTIC CITY, NEW JERSEY.

FURNACE GRATE.

Application filed August 1, 1927. Serial No. 209,986.

The present invention relates to an improved furnace grate, and the purpose of the invention is to provide auxiliary grate members for use on the ordinary or usual 5 grate bars, that is resting on and between them, whereby it is possible to burn a fine grade of coal, such as buck-wheat and rice coal in the furnace, enabling the ashes to pass through, and yet retain a substantial 10 bed of hot coals.

In using the auxiliary grate members it is essential to use a blower for sending a draft through the grate, and to assist in directing the draft upward and at the same 15 time facilitate the passing of the ashes downward to the ash pit, the auxiliary grate members carry fins of elongated construction, depending between the main grate bars. These fins are in the form of blades extending 20 along the length of the auxiliary grate bars or members and are positioned between the main grate bars.

Another purpose is to provide auxiliary 25 grate bars, which may be of the construction as in Figures 1 and 2.

It is to be understood that the particulars herein given are in no way limitative, and that while still keeping within the scope of the invention, any desired modification of 30 details and proportions may be made in the construction of the appliance according to circumstances.

The invention comprises further features 35 and combination of parts to be hereinafter set forth, shown in the drawings and claimed.

In the drawings:—

Figure 1—is a plan view of a main grate 40 of a furnace showing the auxiliary grate bars in position.

Figure 2—is a sectional view on line 2—2 of Figure 1, through the frame of the grate showing the main grate and auxiliary grate 45 bars.

Figure 3—is a sectional view on line 3—3 of Figure 1.

Figure 4—is a perspective view of a portion of a main grate showing an auxiliary grate bar resting on two of the main grate 50 bars.

Figure 5—is a detail sectional view through Figure 4.

Referring to the drawings, 1 identifies a frame, which may be any suitable construction and mounted for rocking movement therein is a plurality of main grate bars, 55 Each main grate bar consists of a transverse bar or casting 3 with which a plurality of discs or plates 4 are carried. These plates 60 or discs may be integral with the bar 3 or mounted thereon in any suitable manner. Preferably the discs or plates 4 are integral with the bar 3.

In fact the bars 3 are adapted to rock in 65 unison through the medium of any well-known mechanism. In other words said bars 3 are interconnected by any suitable means not shown, so that by the rocking movement of one bar 3, all the bars rock in 70 unison, in which case the discs or plates correspondingly move. The discs or plates assume positions as shown in Figure 2, and resting on the edges of the plates 4 and between adjacent series of the plates are 75 auxiliary grate bars 5, which consist of a plurality of relatively small discs 6, which are joined together by the interconnecting pieces 7. In fact the auxiliary grate bars are in the form of castings, and as the main 80 grate bars are rocked the auxiliary grate bars roll back and forth between the edges of the plates 4 of the main grate bars, acting to agitate the coals and thereby permit the ashes to freely pass therethrough.

Depending from the series of discs 6 of the grate bars are fins 8 which are interposed between the opposed edges of the plates 4 of the main grate bars. These fins 85 act as baffles to direct air from a blower 90

upwardly through the grate, and at the same time they assist greatly in agitating and directing the ashes that pass between the main grate bars, and thereby facilitate the passage of the ashes. Adjacent where the fins 8 depend from the relatively small discs, the fins are cut away as shown at 9, corresponding to the spaces between the small discs, which also facilitates in agitating the ashes and facilitating their passage.

Referring to Figures 4 and 5 it will be noted that the fins 8 are eliminated, in which case the auxiliary grate bars simply rest on and between the adjacent edges of the plates 4 of the main grate bars.

The fins 8 are provided with vertical depressions 17 extending from the cut away portions 9 down along the opposed faces of the fins, to permit sections of the fins to be broken off, it being possible to break off one or more of the relatively small discs at the same time, that is broken off at the ends of the auxiliary grate bars.

The invention having been set forth, what is claimed is:

1. In a furnace grate, the combination with main rocking grate bars comprising pluralities of spaced disc plates, of auxiliary grate bars comprising pluralities of relatively small discs joined together, the smaller discs resting edgewise to roll backwards and forwards on and between the edges of the disc plates of the main grate bars.

2. In a furnace grate the combination with main grate bars in parallelism comprising spaced disc plates, of auxiliary grate bars comprising relatively small discs spaced relatively closer together than the disc plates and resting to roll backwards and forwards on and between the edges of the disc plates and adapted to rock back and forth as the main grate bars are rocked.

3. In a furnace grate, the combination with main rocking grate bars comprising pluralities of spaced disc plates, of auxiliary grate bars comprising pluralities of relatively small discs joined together, the smaller discs resting edgewise to roll backwards and forwards on and between the edges of the disc plates of the main grate bars, and depending longitudinal fins carried by the relatively small discs of the auxiliary grate bars, said fins being positioned between the edges of the adjacent main grate bars, and acting to baffle the draft from a blower and direct the same upwardly between the bars.

4. In a furnace grate the combination with main grate bars in parallelism comprising spaced disc plates, of auxiliary grate bars comprising relatively small discs spaced relatively closer together than the disc plates and resting to roll backwards and forwards on and between the edges of

the disc plates and adapted to rock back and forth as the main grate bars are rocked, and depending longitudinal fins carried by the relatively small disc of the auxiliary grate bars, said fins being positioned between the edges of the adjacent main grate bars, and acting to baffle the draft from a blower and direct the same upwardly between the bars.

In testimony whereof he affixes his signature.

FURMAN M. KANDLE.
